FIG. 10

UNITED STATES PATENT OFFICE.

WILLIAM O'N. SHERMAN, OF PITTSBURGH, PENNSYLVANIA.

SURGICAL APPLIANCE.

1,105,105.

Specification of Letters Patent. Patented July 28, 1914.

Application filed February 10, 1912. Serial No. 676,839.

To all whom it may concern:

Be it known that I, WILLIAM O'N. SHERMAN, a citizen of the United States, residing at Pittsburgh, in the county of Allegheny and State of Pennsylvania, have invented a new and useful Surgical Appliance, of which the following is a specification.

My invention relates to appliances employed by surgeons in reducing fractured bones and to the means employed in securing the appliances in position on such fractured bones.

One object of my invention is to provide a surgical appliance or bone plate of improved composition and construction having novel means whereby a maximum strength and degree of stiffness are obtained with the use of a minimum amount of metal and consequent reduction in weight.

Another object of the invention is to provide a surgical appliance or bone plate having novel means whereby the plates are caused to engage or contact with and rigidly support the bones at the point of fracture in maintaining the fractured bones in alined position.

Referring to the accompanying drawings forming part of this specification, Figure 1 is a plan showing a surgical appliance or bone plate constructed and arranged in accordance with my invention. Fig. 2 is longitudinal sectional side elevation of the bone plate shown in Fig. 1. Fig. 3 is a transverse section of the bone plate, the section being taken on the line III—III of Fig. 1. Fig. 4 is a similar section on the line IV—IV of Fig. 1. Fig. 5 is a similar section on the line V—V of Fig. 1. Fig. 6 is a plan partly in section, showing the application of my improved bone plate for use in reducing a fractured bone. Fig. 7 is a transverse section, on an exaggerated scale, taken on the line VII—VII of Fig. 6. Fig. 8 is a side elevation of the screw preferably used in applying the bone plates. Fig. 9 is an end elevation of the screw of Fig. 8, showing the construction of the head thereof. Fig. 10 is a transverse section on the line X—X of Fig. 8 showing the preferred construction of the flutes in the threaded end of the screws.

In the drawings, referring to the Figs. 1 to 5, the bone plate 2, as constructed in accordance with my invention, which is formed of vanadium steel alloy having about

.25 of 1 per cent. vanadium, is provided with a series of holes 3, in which the screws are countersunk on the outer face of the plate and the screws 4 are provided with countersunk heads of the same degree of angularity so as to insure a neat fit between the contacting surfaces of the bone plate and the screws.

The marginal side edges of the plates 2 are sinuous in outline, the wider portions 5 thereof, in which the counter-sunk holes 3 are located, being connected by narrower portions 6 and 7 whose side edges are made up of a series of reverse curves, each curve being tangent to the connecting curves.

In cross section the plates are concave on the inner surface thereof and convex on the outer surface, the concavo-convex cross section affording the greatest possible strength and permitting the thickness of the bone plates to be greatly reduced so as to effect a substantial decrease in weight without sacrifice in strength, while the rigidity of the plates is greatly increased.

The curvature of the concave inner surface of the bone plate is preferably of a smaller radius than that of the bone 8 to which it is applied, so that when in place the marginal side edges of the bone plate will bear against the outer surface of the bone when the plate 2 is drawn tightly into position by the fastening screws 4.

The screws 4 preferably used in fastening the bone plates have a thread 4^a extending closely to about the inner end of the screw head 9. The screw head is countersunk and its outer face is slotted in the usual manner. At about the middle of the length of the slot 10 in the head 9 of the screws 4 is a hole or recess 11 and the screw driver used in inserting the screws in place has a projecting portion which enters the hole 11 in the bottom of the slots 10, so as to prevent sideways slipping of the screw driver in driving the screws 4.

The threaded outer end of the screws 4 is provided with a plurality of lengthwise extending flutes 4^b these flutes acting as a tap in inserting the screws in the bone and overcoming driving the screws into place.

In applying the plates for use in reducing fractured bones, an incision is made at the point of fracture so as to uncover the bone. After the fracture is reduced and the ends 110 of the broken bone 8 are brought in alinement, the bone plate is secured in position

- thereon, removable clamps preferably being employed to temporarily hold the plates in position on the bone. The holes in the bone plate 2 are then utilized as a guide in drilling the holes in the bone, which preferably are made slightly smaller than the diameter of the holding screws 4, or a diameter equal to that of the screws at the root of the screw threads. After the holes have been drilled 10 the screws 4 are inserted in place therein, the threads thereon readily forming internal threads in the drilled holes in the bone in inserting the screws, on account of the flutes 4^b on the outer ends of the screws 4. The 15 screws 4 are driven or screwed into the holes so as to firmly secure the bone plate 2 to the bone 8 and rigidly hold the ends of the broken bone in position, as shown in Fig. 6. The incision is then sewed up and the necessary 20 bandages are put in place.

Ordinarily the bone plates are allowed to remain in place after the bone has knit and the wound has healed, each plate 2 becoming a permanent fixture in such case. In some 25 locations, however, as for example where the flesh or muscles covering the bone are not sufficient, it will be found necessary or desirable to remove the bone plate later, after sufficient time has elapsed to insure proper 30 knitting of the bone.

The advantages of my invention will be apparent to those skilled in the art. By making the bone plates concavo-convex in cross section, the plates are greatly strengthened and stiffened, so that the thickness of the plates can be reduced to a minimum and a materially less amount of metal be used in obtaining the required strength and rigidity. The sinuous outline of the plates avoids a 40 construction having sharp corners or points of intersection, which would form the beginning of a break in the plate. The use of vanadium alloy steel in making the plates very greatly increases the strength and 45 toughness of the metal without lessening its resistance to bending and permits of a much lighter weight plate being used than would otherwise be necessary to afford the requisite strength.

- 50 Modifications in the construction of the bone plates may be made without departing from my invention. The length and width and the degree of curvature in cross section

of the plates may be varied. A greater or lesser number of screw holes may be provided in the bone plates. Screws constructed otherwise than as shown herein may be employed in fastening the bone plates, and other changes may be made within the scope of my invention as defined in the appended 55 claims.

I claim:

1. A surgical appliance comprising a bone plate having a concave inner surface to contact with the bone and openings in said plate through which screws extend into the bone 65 in securing the plate in position thereon, the concave inner surface of the plate having a curvature whereby the marginal side edges thereof contact with the bone when secured 70 thereon.

2. A surgical appliance comprising a bone plate concavo-convex in cross section and having openings through which screws extend into the bone in fastening the plate in 75 position thereon, the concave inner surface of the plate having a curvature whereby the marginal side edges thereof contact with the bone when secured thereon.

3. A surgical appliance for use in reducing fractures, comprising a bone plate concavo-convex in cross section with the marginal side edges of the plate formed of tangentially arranged reverse curves to provide a plate of sinuous outline, said plate having 85 openings therein through which fastening screws extend into the bone in securing the plate in position thereon.

4. A surgical appliance for use in reducing fractures, comprising a bone plate concavo-convex in cross section and having marginal side edges formed of tangentially arranged reverse curves to provide a plate of sinuous outline, said plate having openings therein through which fastening screws 95 extend into the bone in securing the plate in position thereon, the concave inner surface of the plate having a curvature whereby the marginal side edges thereof contact with the bone when secured thereon.

In testimony whereof, I have hereunto set my hand.

WILLIAM O'N. SHERMAN.
